UNITED STATES PATENT OFFICE.

GUSTAV GOERK, OF NEWARK, NEW JERSEY, ASSIGNOR TO THE R. NEUMANN & COMPANY, OF SAME PLACE.

SATCHEL-FASTENING.

SPECIFICATION forming part of Letters Patent No. 655,150, dated July 31, 1900.

Application filed July 10, 1899. Serial No. 723,258. (No model.)

To all whom it may concern:

Be it known that I, GUSTAV GOERK, a citizen of the United States, residing at Newark, in the county of Essex and State of New Jersey, have invented certain new and useful Improvements in Satchel-Fastenings; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The objects of this invention are to simplify the operation of opening satchels and to render the operation more thoroughly automatic, whereby a saving of time is effected and greater convenience attained, to secure such results at a reduced cost of construction, to enable the parts to be applied to a bag or satchel frame by the bag-maker with greater ease and facility, and to secure other advantages and results, some of which may be hereinafter referred to in connection with the description of the working parts.

The invention consists in the improved fastening for bags, satchels, and the like, and in the arrangements and combinations of parts of the same, all substantially as will be hereinafter set forth and finally embraced in the clauses of the claim.

Referring to the accompanying drawings, in which like letters of reference indicate corresponding parts in each of the several views, Figure 1 is a perspective view of a bag or satchel having my improvements. Fig. 2 is a detail view of a bag-frame jaw-section and showing in elevation my improved fastening. Fig. 3 is a central longitudinal section of the lock disconnected from the frame and catches and showing the interior construction on an enlarged scale. Fig. 4 is a plan of the lock-base. Figs. 5 and 6 are detail views of parts of the lock. Fig. 7 is a vertical longitudinal section of one of the catches; and Fig. 8 is a transverse section of the same, on an enlarged scale, taken at line y, Fig. 7. Fig. 9 shows a certain retaining-piece used in assembling the parts of the catch.

In said drawings, *a* indicates a bag or

satchel of any ordinary construction having coöperating jaw-sections, of angle-iron, to which the catches *b* and lock *c* are applied. The said catches are preferably of the usual sliding construction shown in Figs. 7 and 8, where *d* indicates a suitable base-piece adapted to be secured to the bag-frame, and *d'* a slide movable longitudinally upon said base against the power of a spring *d''*, said slide 60 having a downwardly-extending tongue *e*, adapted to engage a coöperating catch member *e'* on the other jaw when the bag is closed.

f is the usual spring-plate, and *f'* the pin for attaching the slide *d'* to the base *d*.

Other constructions of catches may be employed without departing from the spirit and scope of the invention.

The lock *c* is also of a sliding construction similar to the catches described and comprises a base *g*, adapted to be fastened, by means of lugs, screws, or rivets, upon the upper and outer surface of the top flange *a'* of the bag-frame. Said base *g* is upwardly recessed from the bottom or hollow, and apertures *g'* are provided in the side for the entrance of coöperating hooking catch members *c'* on the opposite jaw-section.

An arched top piece *h*, secured at its opposite edges to the top of the base *g*, provides 80 at its open ends, as at *h'*, slideways for pressure-pieces *i*, reduced at one end, as at *i'*, to telescopically enter said slideways. Said pressure-pieces each have a locking-lug *j* projecting downward through suitable slots 85 *j'* in the base *g* to engage the catch members *c'*. Said lugs are so disposed that the bag is locked when the pressure-pieces *i* are projecting from their slideways, and upon the top of the base *g* is pivoted at one end a locking-tongue *k*, adapted to be forced by means of a key between the ends of the pressure-pieces, as is usual, to prevent their inward movement toward one another to unlock the bag. At its outer end and projecting downward from the under side each pressure-piece carries an arm *l*, adapted to move longitudinally with the pressure-piece. Said arm extends downward through the base *g*, slots *l'* being provided therein to allow free movement of the arm, and terminates below the flange *a'* of the bag-frame, which is also slot-

ted to afford a passage. Below said flange a' the extremity of the arm is bifurcated or provided with prongs, as at o , to receive a connecting rod or wire m . The said connecting-wire has preferably a headed extremity n , and the shank of the wire is inserted between the prongs of the arm l by the bag-maker when the parts are assembled upon the bag. After such insertion of the said wire between 10 said prongs of the bifurcated arm the said prongs are closed together by pliers or other means convenient for service and the arm l thus fastened to the wire m . The said prongs when closed together, however, do not clamp 15 the wire, but permit a free sliding movement of the wire within the eye formed by the closed prongs for purposes hereinafter more fully described. The said connecting-wires m extend longitudinally beneath the flange a' of the bag-frame and at their outer ends 20 are linked or provided with an eye, whereby each wire is securely fastened to a catch-arm e , said arm being perforated, as at p , to receive the wire.

25 By means of the connecting-wires m , extending from the lock c to the catches b , I am enabled to open both the lock and the catches by one operation or pressure. Thus the operator by pressing the pressure-pieces i 30 toward each other not only releases the lock, but also by the wires m causes the slides d' of the catches to move longitudinally against the springs d'' to release the catching members. The springs d'' then cause a return of 35 the slides d' and pressure-pieces i when released to their original position. Said springs may be arranged in any suitable manner adapted to return the parts to normal positions, so that the jaws of the bag will be automatically locked when pressed together. It will be evident that instead of their being 40 arranged in only the catches, as shown, both the lock and catches may be provided with independent springs, or in some cases springs 45 in the lock could effect a return of both pressure-pieces and catches.

While I have shown and described a preferred construction of the lock, catches, and the connecting parts, I am aware that various 50 modifications may be made without departing from the spirit or scope of the invention, and I do not wish to be understood as limiting myself by the positive descriptive terms

employed excepting as the state of the art may require.

It will be seen that the construction described provides a quick and easy method of opening a bag, such as renders the device especially applicable to physicians' satchels, cases, and the like, while the bag is as securely closed as in constructions formerly used.

Having thus described the invention, what I claim as new is—

1. In a bag, the combination of a middle lock comprising an apertured case fastened to one jaw of the bag and open at both ends, catches on the opposite jaw adapted to enter said case, pressure-pieces sliding telescopically in the opposite open ends of the lock-case, and adapted to engage said catches, rigid arms projecting downwardly from said pressure-pieces, end catches upon the bag having downwardly-projecting sliding tongues, and connecting-wires extending from said arms to said tongues, substantially as set forth. 65

2. In a bag, the combination with end catches having sliding tongues projecting within the bag, of a central lock comprising a casing arranged on one jaw and adapted 70 to receive hook projections on the other jaw, pressure-pieces adapted to engage said projections sliding in said casing and having downwardly-extending arms, and connecting-wires extending from said arms to said 75 tongues, substantially as set forth.

3. In a bag, the combination of a lock providing a longitudinal slideway open at both ends, pressure-pieces sliding telescopically into said slideway and having downwardly-extending arms, end catches on the bag having downwardly-projecting catching-tongues, connecting-wires extending between said arms and tongues and being provided with a sliding connection at one end, whereby said 90 lock and end catches are operated simultaneously, and springs returning said parts to normal positions, substantially as set forth. 95

In testimony that I claim the foregoing I have hereunto set my hand this 6th day of July, 1899.

GUSTAV GOERK.
